UNITED STATES PATENT OFFICE.

MEYER S. HESS, OF BALTIMORE, MARYLAND.

SHOE.

1,379,564.

Specification of Letters Patent. Patented May 24, 1921.

Application filed May 27, 1918. Serial No. 236,837.

To all whom it may concern:

Be it known that I, MEYER S. HESS, a citizen of the United States of America, residing at Baltimore city, in the State of Maryland, 5 have invented new and useful Improvements in Shoes, of which the following is a specification.

The purpose of the invention is to provide a new and useful construction for shoes in 10 the form of a composite insole whereby the usual insole is employed but becomes a sub-sole in the improved construction and has superimposed upon it a supplemental insole or what is known throughout this construction 15 as a super-sole. In the improved construction there is employed the common way of forming the sub-sole with its marginal rib for the purpose of securing the welt thereto and the feather left by the forming 20 of this rib serves as a means for the attachment of the super-sole which is channeled in a new and novel way to provide a marginal feather for interlocking connection with the feather formed on the sub-sole. 25 This particular construction provides for the use of the ordinary leather insole or the cheap paper insole, either one of which is reinforced and made relatively thick and substantial when the improved super-sole is 30 attached. The super-sole is made preferably of a chemically treated felt material having waterproofing qualities, flexibility and comparatively great wearing qualities. It takes the place of the sock lining employed to cover the usual insole and all told 35 greatly simplifies the construction and reduces the cost of production of the shoe in which it is used, aside from providing the other advantageous features referred to 40 above.

In the drawings which accompany this specification and form a part thereof:

Figure 1 is an elevational view of a shoe employing the improved insole, the upper 45 and outer sole being broken away so as to show the improved insole in longitudinal edge elevation.

Fig. 2 is a transverse sectional view taken in the vicinity of that part of the insole on 50 which the ball of the foot rests.

Fig. 3 is a detail sectional view of the improved insole taken in a longitudinal direction from the point of the toe to a point just back of the toe. This for the purpose of

showing the means for securing the super- 55 sole to the sub-sole when the shoe construction is of a pointed toe style.

Fig. 4 is a detail sectional view showing how the super-sole is cut to provide means 60 for attaching it to the sub-sole.

Fig. 5 is a detail sectional view showing how the sub-sole is channeled or cut to provide its marginal rib and feather.

Fig. 6 is a detail bottom plan view showing the securing strip for the toe of the 65 super-sole when the composite insole is used with a pointed toe shoe.

To illustrate the invention, there are shown the usual shoe elements consisting of the upper 1, the outer sole 2 and the welt 3. 70 With these elements there is associated the improved composite insole consisting of the sub-sole 4 and the super-sole 5. The sub-sole is provided with the usual marginal rib 6 formed by means of a channeling machine 75 which cuts webs of material from the body of the said sub-sole. These webs are turned down to a position substantially perpendicular to the surface of the said sole and thereby leave a marginal feather 7 tapering 80 in thickness away from the said rib, so that the thinnest portion of the feather is at the extreme edge of the said sub-sole.

The super-sole 5 is attached on top of the sub-sole 4 and this super-sole is cut to agree 85 in plan dimensions with the dimensions of the shoe with which the improved composite sole is to be used. On its under face the super-sole is channeled adjacent to its marginal edge so as to leave a feather 8, the 90 channeling being done in a direction toward the marginal edge in order that the said feather 8 may be joined with the super-sole at the marginal edge and be directed inwardly therefrom. This channeling is done 95 to within one-eighth or one-sixteenth of an inch of the extreme edge of the super-sole, thereby leaving the one-eighth or one-sixteenth inch thickness of stock to serve as a means by which the feather 8 remains attached to its attendant sole.

If, in the preparation of the feather 8, the channeling is done to within one-sixteenth of an inch of the edge of the super-sole, the sub-sole 4 in plan dimensions is made 105 smaller by this amount than the plan dimensions of the super-sole. If the channeling by which the feather 8 is formed is done to

within one-eighth of an inch of the edge of the super-sole, the plan dimensions of the sub-sole are reduced by this amount.

The feather 8 having been formed on the 5 bottom face of the super-sole, this feather is thrown back and the sub-sole is placed against the under face of the super-sole with its top face against the under face of the latter. Then this feather 8 is brought 10 up against the under face of the feather 7 to which it is secured by any suitable means, preferably cement, and then turned down against the outer face of the rib 6.

The sub-sole 4 is so prepared that the rib 15 6 terminates at the beginning of the heel portion 9 of the sub-sole and the equivalent portion 10 of the super-sole lies on top of this heel portion 9 to which it may be secured by cement or other suitable means, the 20 interlocking feathers being omitted in the heel portion of both elements of the composite insole.

If the shoe constructed in accordance with this invention be of the broad toe style, the 25 marginal feather 8 is extended around the toe, since a channeling machine may be operated to provide the continuous formation of this feather beginning at the heel on one side and extending continuously around the 30 toe to the beginning of the heel on the other side. If, however, the shoe being constructed has a toe of the pointed style, the feather 8 cannot be made continuous because of the impracticability of carrying the channeling 35 around the apex of the toe.

By referring to Fig. 3 it will be readily seen how the improved super-sole is attached to the sub-sole at the toe when the latter is pointed. A strip 11 is employed 40 and secured adjacent to the marginal edge of the pointed toe of the super-sole 5 by a line of stitching 12. This strip is then made to embrace the feather 7 and the rib 6 on either side of the apex of the toe and is secured to both the inner and outer face of the rib by cement or any other suitable means.

The composite insole having been prepared in the manner above described, the 50 welt 3 is secured by a line of stitching 14 to the marginal rib 6, as is usual in shoe construction, but the feather 8 of the super-sole is interposed between the welt and the rib and the stitching 14 serves to secure this feather and further it serves to secure the 55 sub-sole to the welt by engaging its marginal rib 6. Of course the upper 1 is secured to the welt and to the composite sole by the stitching 14 and its position relative to those parts is the same as is common in 60 shoe construction.

That the outer sole 2 may be secured to the welt, the line of stitching 15 is employed, this, of course, being one of the usual means for attaching the outer sole to the vamp.

65 It will be observed that the improved

composite insole provides for the obtaining of a relatively thick and substantial insole and thereby the obtaining of a relatively strong and substantial shoe with the use of an inexpensive sub-sole which, by itself, is 70 of insufficient strength to stand the strains or retain its shape. Leather of thickness and quality for use as insoles as heretofore constructed being very scarce and expensive, the improved construction described above furnishes a substitute insole which has the desired thickness, strength and flexibility and has the further advantages of being practically moisture, heat and cold proof, has a non-curling feather, 80 and presents a smooth and comparatively soft surface to the foot.

While the invention has been defined as a composite insole consisting of a leather sub-sole and a super-sole super-imposed thereon, it is obvious that the composite insole may comprise a sub-sole made of cheap material, such as pasteboard or materials possessing similar characteristics. While it is intended that the super-sole shall be made of a specially prepared chemically treated felt material, it is apparent that any other material serviceable as a super-sole may be employed without departing from the spirit or sacrificing any of the advantages of the 95 invention.

The invention having been described, what is claimed as new and useful is:

1. A composite insole comprising a plurality of layers having mutually engaging 100 overlapping extensions by which they are interlocked.

2. A composite insole comprising a plurality of layers having mutually engaging overlapping extensions adjacent their marginal edges by which they are interlocked.

3. A composite insole comprising a sub-sole and a super-sole, the two said soles having 105 interlocking feathers by which they are attached together.

4. A composite insole comprising a sub-sole and a super-sole, the two said soles having interlocking feathers by means of which they are secured together at their marginal edges.

5. A composite insole comprising a sub-sole and a super-sole super-imposed upon the sub-sole, the two said soles having oppositely disposed feathers on their contacting faces which feathers may be made to 120 interlock to secure the two said soles together.

6. A composite insole comprising a sub-sole and a super-sole super-imposed upon the sub-sole, the two said soles being provided at their marginal edges with opposed feathers which interlock to secure the two said soles together.

7. A composite insole comprising a sub-sole formed with a marginal feather taper-

ing in thickness, and a super-sole super-imposed upon the sub-sole and also formed with a marginal feather oppositely disposed with reference to the feather of the sub-
5 sole, the feather of the sub-sole engaging between the feather and the body of the supersole to secure the two said soles together at their marginal edges.

8. A composite insole comprising a sub-
10 sole having a feather wedge-shaped in cross-section and a super-sole super-imposed upon the sub-sole and also having a feather wedge-shaped in cross-section but opposed to the feather of the sub-sole, the feathers
15 on the said two soles engaging to hold the two soles together.

9. In a shoe having an upper, an outer sole and a welt secured to the outer sole, a composite insole consisting of a subsole and
20 a super-sole, the sub-sole being formed with

a marginal rib, the super-sole being formed with a marginal feather, and means for securing the marginal rib, the marginal feather, the upper and the welt together.

10. In a shoe having an upper, an outer 25 sole and a welt secured to the outer sole, a composite insole consisting of a sub-sole and a super-sole, the sub-sole being formed with a marginal rib and a marginal feather outside of the rib, the super-sole being 30 formed with an inwardly directed feather on its marginal edge, the feather of the super-sole embracing the feather of the sub-sole and lying against the outer face of the rib of the latter, and means for securing the 35 welt, the upper, the feather on the super-sole and the rib of the sub-sole together.

In testimony whereof I affix my signature.

MEYER S. HESS.
